TIMER FOR INTERNAL COMBUSTION ENGINES

Louis Beeh and Wolfgang E. Schwarzmann, Longmeadow, Mass., assignors to United American Bosch Corporation, Springfield, Mass., a corporation of New York

Application December 9, 1932, Serial No. 646,476

4 Claims. (Cl. 200—21)

Our invention relates to an improvement in timers for internal combustion engines and particularly to a timer comprising a circuit breaker and distributor for the ignition circuits of engines for air craft.

An object of the invention is to provide a timer which is compact and simple in construction but strong and durable and capable of being used in connection with the ignition circuits of internal combustion engines carrying a relatively large number of cylinders.

The nature, objects and advantages of the invention are fully set forth in the ensuing description and the novel features are pointed out in the appended claims. This disclosure, however, is illustrative only and changes may be made in details without departing from the spirit of the invention or exceeding the scope of the appended claims.

On the drawing:

Fig. 1 is a longitudinal section of the timer according to our invention;

Fig. 2 is a plan of the circuit breaker and the method of mounting same;

Fig. 3 is a front elevation of the device with the shield removed; and

Fig. 4 is a view of a detail.

On the drawing the same numerals identify the same parts throughout.

On Fig. 1, the numeral 1 indicates a cap-shaped casing in which the circuit breaker is mounted; this casing being closed at one end and open at the other to receive the hollow distributor head 2; which is of insulation and which carries fixed high tension terminals 3 to be connected to the spark plugs. The rotor of the distributor, also of insulation, is shown at 4 within the head 2. Embedded in the rotor is a conductor element or brush 5 in contact with which is a terminal 6 carried by the head 2 in line with the axis of rotation of the rotor; this brush 6 being disposed in a suitable conducting socket 7 embedded in the head 2 at the inner end of a boss 8 on the exterior of the head 2. The terminals 3 are affixed to the head 2 at the inner ends of similar sockets and the entire distributor head is housed in a suitable metallic shield consisting of a front section 9 and a rear section 10. This shield has necks 11, preferably diametrically opposite to each other, although they may be otherwise placed, and through these necks the conductors to be attached to the contacts 3 and the brush 6 are led. The outer ends of the terminals 3 and of the sockets 7 have bores in which the ends of said conductors can be secured. The conductor

connected to the brush 6 will of course lead to the spark coil of the engine and those connected to the terminals 3 will run as before stated to the igniters of the various cylinders.

The distributor head 2 has a ring 12 of suitable material embedded in the outside lateral surface thereof; and this ring abuts the rim of the casing 1 which encircles and receives within it the rim of the head 2. The section 10 of the shield enveloping the head 2 has an inside flange 13 forming a shoulder which abuts this ring and when the shield is secured to the casing 1 the distributor head 2 is therefore held tightly in place.

The shaft which operates the timer is indicated at 14, this shaft passing into the casing through the closed end and it carries on its inner end a tubular shaft or sleeve 15 to which the rotor 4 is affixed. On said sleeve is also mounted the breaker cam 16. The contacts of the breaker are mounted on a plate 17 in the casing 1 and this plate carries interrupter levers 18, shown as two in number, mounted on journals or pivot posts 19 affixed to the plate 17. Of course, the number of circuit breakers or interrupters may be varied as circumstances may dictate. The interrupter levers 18 are of insulation but each carries a strip of metal 20, one end of which bears against the cam 16 and the other of which carries a movable contact to engage and disengage a fixed contact supported on a member 21 attached to the plate 17. These members 21 are secured to plates 22 affixed to the base plate 17 and at 23 are springs attached to the breaker levers 18 at one end and at the opposite end to fixed upright projections 24 which may be made in one piece with the plates 22. These springs hold the fixed and movable contacts together, but when the projections on cam 16 engage the adjacent end of the metal strips 20, the fixed and movable contacts are separated from each other. At 25 on the base plate 17 is a binding post which is preferably insulated from the base plate 17 and connected by a suitable conductor 26 to one of the spring strips 23, and the projections 24 to which these spring strips 23 are anchored are preferably connected by a curved conducting strip 27. These projections 24 as well as the binding post 25 and the springs 23 are preferably insulated from the base plate 17 and the members 21 which carry the fixed contacts should be connected to this base plate. The two circuit breakers open in succession, but one remains open until after the other is open so that, for a short space of time, the circuit of the primary coil connected to the binding post 25 will be completely broken. At 28 is a condenser held

100
105
110

fast on the base plate 17 by a clip 29 and this condenser is connected by a conductor to the projection 24 to which is secured the spring 23 of the circuit breaker 18 which opens after the other 5 circuit breaker is actuated by the cam 16. As shown in Fig. 2, the lower circuit breaker opens first and then the other follows. The lower one then closes before the upper so that there is a short period during which the primary circuit 10 is fully interrupted. The closing of the contacts of the lower circuit breaker enables the primary circuit to be reestablished quickly in time for the next spark in the cycle of operations of the engine.

The sleeve 15 projects through the plate 17 and 15 carries on its adjacent end a fixed head 30 with which is made fast a plate 31. The shaft 14 carries a cap-shaped element 32 rigidly secured thereon, and projecting within the head 30 is a section 33 of the shaft 14 providing a shoulder which 20 abuts the sleeve 15. From the section 33 a reduced portion of the shaft 34 enters the sleeve 15. At 35 are diagrammatically indicated governor weights housed between the elements 31 and 32 and suitably connected to both of these parts. 25 Hence when the shaft rotates the governor will shift the plate 31 with respect to the plate 32 and advance or retard the sleeve 15 and cam 16.

The end of the casing 1 remote from the head 2 has a bore for receiving the shaft 14, this bore being counter-bored at 36 to receive a lubricating 30 washer and at both ends of this bore are ball bearings 37 for the shaft 14. The same end of the casing 1 has projections 38 with openings to enable the entire construction to be suitably 35 mounted on the framework of the engine. At 39 in the rim of the casing 1 at a suitable point is a bushing thru which the low tension lead of the ignition circuit can be passed and be secured to the binding post 25.

40 To hold the sections 9 and 10 of the shell enveloping the head 2 together and to make them fast on the casing 1, we employ suitable bolts with nuts 41, these bolts passing through perforated lugs 42 on the sections 9 and 10 into suitable lugs having perforated openings 43 in the casing 1. The ring 12 may have notched 45 projections 44 which extend out through recesses in the rim of the section 10 adjacent the flange 13 to be engaged by the bolts 40 to hold the head 2 against turning. This construction is shown in Fig. 4 but only the section 10 of the shield is included, this section carrying a lug 42. It will be understood, however, that the section 9 will have similar lugs at each side for this purpose.

55 The base plate 17 rests against a shoulder 45 in the casing 1 and is secured in any suitable

manner. The central opening to afford clearance for the sleeve 15 and head 30 is shown at 46.

The openings 47 in the flange 38 may of course be elongated to allow the casing 1 to be shifted angularly and made fast in adjusted position.

Having described our invention, what is claimed is:

1. A timer comprising a casing, a distributor head mounted on one end of the casing, a hollow shield enveloping said head at the front and sides of the latter, said shield comprising matched sections, and means engaging the sections, the head and the casing, to secure said parts together, said shield having an outlet neck for conductors attached to said head.

85 2. A timer comprising a casing, a distributor head of insulation with its rim telescoping within the rim of the casing, a ring encircling the exterior of the distributor head embedded therein and abutting the rim of the casing, a shield enveloping the distributor head and having a rim abutting said ring and means for holding the shield, the distributor head and the casing together, said shield having an outlet neck for conductors attached to said head.

90 3. A timer comprising a casing, a distributor head of insulation with its rim received within the rim of the casing, an outside ring embedded in the rim of the distributor head and abutting the rim of the casing, and a shield enveloping said distributor head and having a rim which encircles said ring, said last-named rim having an inside shoulder abutting said ring, said ring having notched projections extending beyond the rim of the shield, and fastening bolts to engage 105 perforated lugs on the outside of the shield and casing to hold said parts together, said notched projections receiving said bolts, said shield having an outlet neck for conductors attached to said head.

110 4. A timer comprising a casing, a distributor head of insulation with its rim received within the rim of the casing, an outside ring embedded in the rim of the distributor head and abutting the rim of the casing, and a shield enveloping said distributor head and having a rim which encircles said ring, said last-named rim having an inside shoulder abutting said ring, said ring having 115 projections extending beyond the rim of the shield, and fastening means to engage the outside 120 of the shield and casing to hold said parts together, said projections engaging said fastening means.

125 LOUIS BEEH.
